UNITED STATES PATENT OFFICE

148,091

DESIGN FOR A BASE FOR A MOTION PICTURE PROJECTOR OR THE LIKE

Jean O. Reinecke, Oak Park, Ill., assignor to Bell & Howell Company, Chicago, Ill., a corporation of Illinois

Application September 17, 1946, Serial No. 133,362

Term of patent 14 years

(Cl. D61—1)

To all whom it may concern:

Be it known that I, Jean O. Reinecke, a citizen of the United States, residing at Oak Park, in the county of Cook and State of Illinois, have invented a new, original, and ornamental Design for a Base for a Motion Picture Projector or the like, of which the following is a specification, reference being had to the accompanying drawing, forming a part thereof.

In the said drawing—

Figure 1 is a top plan view of a base for a motion picture projector or the like, embodying my new design;

Figure 2 is a side elevation of the same; and Figure 3 is a front elevation of the same.

The back and side of the base which are not shown are substantially plain.

I claim:

The ornamental design for a base for a motion picture projector or the like, as shown and described.

JEAN O. REINECKE.
